UNITED STATES PATENT OFFICE.

ALEXANDER JAMES ANDREWS, OF PORTLAND, OREGON.

BARBER'S PAPER AND CHECK.

1,189,899.

Specification of Letters Patent.

Patented July 4, 1916.

Application filed September 9, 1915. Serial No. 49,775.

To all whom it may concern:

Be it known that I, ALEXANDER J. ANDREWS, a citizen of the United States, residing at Portland, in the county of Multnomah and the State of Oregon, have invented 5 certain new and useful Improvements in Barbers' Paper and Checks, of which the following is a specification.

The head rests of many barbers' chairs 10 now in common use are provided with rolls of paper adapted to be drawn over the head rests to protect the customers for sanitary reasons and the paper from the rolls is to be torn off in sections so that each section may 15 be used for depositing the lather waste.

The present invention relates to such paper for head rests of barbers' chairs having a cashier's check formed therein and an object of the invention is to provide a check 20 for each section of such paper to furnish an accurate and economical system of bookkeeping for each barber's chair in every shop.

The preferred means by which I accomplish the objects of the invention are illustrated 25 in the accompanying drawing forming part of the specification which will be hereinafter specifically described.

In the drawings, Figure 1, is a plan view 30 showing a portion of the strip of paper from the roll. Fig. 2, is a plan view of one of the sections severed from the strip of paper upon which the lather waste is deposited, and Fig. 3, is a plan view of one of the cashier's checks severed from the section of the 35 strip of paper.

Referring to the accompanying drawing like and corresponding parts are designated by similar reference characters throughout the several views.

40 In Fig. 1, of the drawing is shown a strip of paper forming part of the roll adapted to be carried by the head rest of the barber's chair. This strip of paper is shown divided into three sections each being indicated by 45 the numeral 1 and each section is provided in the upper left hand corner thereof with a cashier's check 2. In practical use the rolls of paper are carried by the head rest of the barber's chair and the strip of paper 50 is drawn over the head rest to protect the customer's head and one of the sections of the strip projects beyond the toothed knife carried by the head rest so that each section may be severed from the strip. When each 55 section is severed from the strip that section is used by the barber to deposit the

waste lather thereon and the check 2 is given to the customer who later gives the same to the cashier of the barber's shop when paying for the services rendered him. Each check 60 has marked thereon the number of the chair from which it comes and the number of the check. This affords a complete book-keeping system for the cashier as the number of occupants to each chair can be readily as- 65 certained.

When a customer seats himself within the barber's chair one section of the paper projects from the head rest of the chair and when the barber is ready, it is torn off and 70 used for the lather waste of the customer seated within the chair. When the barber has finished this job on the customer he then takes a pencil and marks on the check 2 of the following section which is still held firmly 75 in place by the head rest the amount of the work just finished. Then the barber pulls out or runs out the strip of paper sufficiently to sever the check along the line 3 and immediately severing the entire check, handing the same to the customer just finished. When the next customer is seated the section 80 projecting from the head rest is torn along the line 4 and that section as shown in Fig. 2 of drawings is used for depositing the 85 lather waste from the customer seated within the chair. By so constructing the strip of paper it is obvious that only a short line indicated by the numeral 5 is perforated therefore the strength of the paper is not 90 impaired. It will also be noted that no additional paper is necessary to form the check other than the strip forming the ordinary rolls now in use and that each section when attached to the strip will completely cover 95 the head rest providing the usual sanitary cover therefor.

Whereas, I have shown and described a simple and preferred means for carrying out the invention it is to be understood that 100 no limitation is necessarily made to the precise structural details therein exhibited, but the right is reserved to any changes or modifications that come within the scope of the invention without departing from the spirit 105 thereof or sacrificing the efficiency of the same.

Having fully described my invention, what I claim as new and desire to secure by Letters Patent is:—

110 1. The combination with a strip of paper for the head rests of barbers' chairs com-

- 2
- prising a plurality of sections, a check formed integrally in one corner of each section and adapted to be severed therefrom, for the purpose set forth.
- 5 2. A barber's paper and check comprising a roll of a continuous strip of paper, said strip being divided into a plurality of sections adapted to be severed, an integrally formed check within one corner of each section, the inner ends of said checks adapted to be severed from the sections, and one edge of the check being perforated for the purpose of facilitating its detachment from the section.
- 10 15 3. A barber's paper and check consisting
- of a roll of paper comprising a plurality of sections adapted to be severed from each other, a check formed integrally within one corner of each section having one end thereof adapted to be severed from the section in 20 which it is formed, and one edge of the check being perforated.

In witness whereof, I hereunto subscribe my name to this specification in the presence of two witnesses.

ALEXANDER JAMES ANDREWS.
